UNITED STATES PATENT OFFICE.

JOHN HENRY HORNE, OF LAWRENCE, MASSACHUSETTS.

ROLL FOR PAPER-PULP ENGINES.

SPECIFICATION forming part of Letters Patent No. 310,203, dated January 6, 1885.

Application filed August 27, 1884. (No model.)

To all whom it may concern:

Be it known that I, JOHN HENRY HORNE, a citizen of the United States, residing at Lawrence, in the county of Essex and State of Massachusetts, have invented certain new and useful Improvements in Rolls for Paper-Pulp Engines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to a class of pulp-engines in which a male grinder, cone shaped or cylindrical, and furnished with knives, is adapted to enter and fit a similarly-shaped shell, the inner periphery of which is armed 20 with a series of longitudinal blades or knives similar to and co-operating with those on the male grinder.

My present invention may be considered an improvement on the invention shown in Letters Patent of the United States No. 163,728, issued on the 25th day of May, 1875, and is based on the manner of constructing the periphery of the male grinder or cone to which the blades are attached and secured, whereby 30 a deeper filling of wood is obtained and the knives maintained securely and rigidly in position until worn out, which cannot be done, by the means shown in the above-mentioned invention as hitherto constructed.

The drawings represent, in Figure 1, a vertical longitudinal section of a roll embodying my improvements with a knife in position, while Fig. 2 is a similar section of the roll without the blade. Fig. 3 shows a longitudinal section of a roll as made in the old form for purposes of reference, and Fig. 4 a cross-section of same. Fig. 5 represents a like section of a roll embodying my improvements.

To a complete understanding of my invention it will be necessary to describe somewhat briefly the method of fastening the knives in rolls as hitherto practiced, and thus define more precisely and clearly the advantages embodied in my improvements.

In the drawings accompanying this specification I have shown in Fig. 3 a longitudinal section of a roll or grinder, which is repre-

sented at A as frusto-conical in shape. The shell is shown at a, and in the periphery of the latter are created a series of longitudinal 55 grooves, b, (represented by the dotted line,) which receive the blades, one of which is shown at B. Transversely of the said periphery are cut or turned a series of annular channels, c c, while one side of the ribs d d 60 intervening between the channels is undercut, by which overhanging horizontal lips e e are formed. Similarly the blades B B are constructed with a series of transverse cuts or notches upon their lower edges, with projections g g corresponding to those formed on the periphery of the shell a, but oppositely disposed in order that the spurs g g on the blades interlock with the lips or spurs e e on the shell shall secure and fasten the blades 70 to the roll. In this manner of securing the knives or blades, by examining the drawings it will be observed that the latter rest upon the bottom of the longitudinal grooves b b, the latter being cut as deep as the annular 75 concentric channels c c; hence when the blades B B are in position a part of the lower edge of the latter is buried in the shell a of the roll, while the wood filling resting upon the periphery of said shell is necessarily made less 80 deep, (compare Figs. 4 and 5,) and with less holding power, owing to the small bearing-surface of the blade exposed; as a consequence, the blades upon being worn to any extent become loose, and consequently ineffective, and 85 new bars must be substituted. It is to overcome these objections that I have constructed the periphery of the roll C in the manner I have done, which is shown as of the usual form adopted in pulp-engines of this class, 90 with an outer shell, D, integral on its periphery, but provided with a series of annular concentric rings, E E, &c. These rings may be cast integral with the shell, or may be made separately and shrunk on. In either case they 95 would be undercut, forming projecting lips h h, which will engage and interlock with the spurs or shelves g g, formed on the blade, as previously described. A prominent difference in the construction of the periphery of the shell a of the roll A from the shell D of the roll C is that the longitudinal grooves b b in the first case are necessarily cut as deep as the bottom of the annular channels c c, in or-

der to admit the blade sufficiently to interlock the parts *e e* with *g g*. This lessens the depth of the wood filling *F* by the depth the blade enters the shell *a* of the roll. On the other hand, in the construction I propose to adopt the entire depth of the blade is above the periphery of the shell *D* of the roll *C*, except that portion which enters and fills the grooves *b' b'*, the depth of which is just sufficient to steady the lower edge of the blades and maintain them in their proper relative positions before the wood filling is inserted. This is effected by leaving in lieu of the channels *c c* the annular projecting ribs or rings *E E*.

The strips *F F* of wood filling adapted to my improvements have transverse cuts, slots, or recesses *h'*, corresponding in position and depth to the annular ribs *E E* upon their lowest edge, and hence when the filling is driven home it rests on the outer periphery of the roll supporting the bar its entire depth, and an increased depth of filling is obtained by the height of the annular ribs *E E*, which hitherto have been sunk in the periphery or shell of the roll. Each of these ribs is undercut on one side, forming an annular flange, *h*, and each of these recesses or slots *h'* of the blades *F* is so shaped as to leave a tongue, *h'*, for engaging with one of said annular flanges. Furthermore, after the blades are applied to the ribs by interlocking, the wood filling *F F* is driven in, and the full depth of the bar is exposed for a bearing-surface, which allows the bars to completely wear down without becoming loose, and this is effected solely by the greater depth of wood filling, which bears

against the blades and maintains them rigidly fixed.

It will be noticed in the section of the roll embodying my invention, Fig. 2, that slight depressions *i i* are formed in each side of the ribs *E E*; but this is simply to allow the planing-tool to enter in creating the slight grooves *b' b'* for the purpose above premised. Thus it will be seen that by constructing the periphery of the roll in the manner I have set forth I can procure with a bar of the same depth a much deeper space for the wood filling, consequently a greater bearing-surface by which the blades are maintained fixed, and a better roll obtained, inasmuch as the bars or blades can be used a longer time and the roll requires filling less often, since the bars can be kept rigid and fixed until completely worn out.

I claim—

1. The roll *C*, having annular ribs *E* raised thereon, each rib being provided on one face with a projecting annular flange, *h*, in combination with a series of blades, *F*, each of which has in its inner edge a series of recesses, *h'*, forming tongues *h'*, which interlock with said flanges *h*, substantially as set forth.
2. The roll *C*, having longitudinal grooves *b'* and unbroken undercut annular ribs *E*, in combination with blades *F*, which fit into grooves *b'* and interlock with said ribs, substantially as set forth.

In testimony whereof I affix my signature in presence of two witnesses.

JOHN HENRY HORNE.
